LATCH CONSTRUCTION

Charles L. Frost, Grand Rapids, Mich.

Application July 13, 1935, Serial No. 31,145

2 Claims. (Cl. 292—16)

This invention relates to latch constructions and is particularly concerned with a very simple and economical latch which may be applied to various articles such as cupboards, cabinets 5 and the like, and in which the two parts of the latch may be interchangeably applied, one to a door and the other to a relatively fixed portion of the structure on which the door is mounted, or they may be reversed in position and application. In addition the latch structure is one which has capability of attachment in many different positions and in different planes so that it has a wide field of application in its connection to doors, door frames, shelves or the like.

One feature of my invention resides in the balanced application of pressure against the keeper member whereby the keeper member is not subjected to any cantilever bending force and consequently it may be made of relatively 20 thin metal. This fact aids in its construction inasmuch as it is desirable to make it of thin metal in order to permit the sides thereof to move toward and away from each other. This movement oftentimes occurs or rather this movement is desirable when the screws are driven 25 through the base of this member so as to cause the separated base portions to aline themselves with the axes of the screws. In other words even though the base screws being slightly placed off 30 center, nevertheless this will not prevent the heads thereof from being brought to a flush position against the bases due to the novel resilient construction thereof.

Another advantage is that the springs contacting the latch member press evenly thereagainst and do not tend to twist the door hinges assuming that the axes of the hinges are located in parallelism to the axes of the spring pressed 35 plungers. If my improved device is located with the axis of the spring plungers perpendicular to the door hinges then the springs of the plungers takes care of the expansion of the door. If the axis of the spring pressed plungers is located in 40 parallelism to the hinges of the door then the expansion of the door is taken care of by the elongated slots in the keeper.

Another feature of my invention resides in the provision of marking means upon the keeper member whereby the same may be easily installed in its exactly correct position.

Yet another advantage resides in the symmetrical construction of my elements whereby they may be either installed in a right-hand position 45 or a left-hand position.

The invention and the construction embodying the same may be understood from the following description, taken in connection with the accompanying drawing, in which,

Fig. 1 is an elevation partly in section illustrating the latch in use. 5

Fig. 2 is a plan view thereof.

Fig. 3 is a plan view of the keeper part of the latch structure.

Fig. 4 is a horizontal section through the upper 10 part of the complementary member of the latch which is used with the keeper.

Fig. 5 is a perspective view of the keeper, and

Fig. 6 is a perspective view of the other or complementary latch member. 15

Like reference characters refer to like parts in the different figures of the drawing.

In the construction of the latch, (Fig. 6) a plate of flat metal is formed so as to have a flat wing 1 the full width of the plate, which is adapted to 20 be placed flat against the member to which it is to be attached, screws passing through suitable openings made in the wing for purposes of attachment. This plate is bent at right angles making two spaced apart extensions 2 and 3 25 which are separated by a slot 4. The ends of the extensions 2 and 3 are rolled into clamping rolls 5 and 6, respectively.

Within each of the rolls 5 and 6 a bullet catch 30 is clamped and held. Each catch comprises a thin sheet metal housing 7 open at one end and closed at the other, with an opening through the closed end. A movable latching member is mounted in the housing comprising a head 8 fastened to or integral with a stem 9, the stem 35 extending through the opening in the closed end of the housing 7, and with a coiled compression spring 10 between the inner side of the head 8 and the closed end of the housing 7. The outer end of the stem 9 is upset so that it will not pass 40 back through the opening through which it is passed initially in assembling. The outer end of the head 8 is rounded and curved into semi-spherical or bullet shape. With two of the bullet catches thus mounted opposite to each other, one 45 clamped in each of the rolls 5 and 6, the two heads 8 slightly contact each other when projected by the springs 10 to their outermost positions, as shown in Fig. 6.

The keeper member, which is to cooperate with 50 the latching structure described is made from a single piece of flexible flat material bent midway between its ends so as to provide two spaced apart sides 11 and 12 which are connected at 13. Each of the sides 11 and 12 is provided with an 55

elongated slot 14, the two slots in the two parts lying directly opposite each other. The outer ends of the parts 11 and 12 are turned at right angles making two attaching ears 15 through which screws may be passed to secure the keeper to a member upon which it is to be mounted. The connection at 13 between the sides 11 and 12 is of a pointed character so that it will insert between the heads 8 of the opposite catches and force the same apart until the heads 8 reach the slots 14 whereupon the same enter said slots under pressure of the springs 10. The structure permits the sides 11 and 12 to some adjustment whereby the screws, inserted through the attaching ears 15, may be driven to a full and complete entry with their head flush and against the ears. Each of the ears 15 has a projection 15a as shown in Figs. 3 and 5.

In Figs. 1 and 2 the first described structure which carries the bullet catches is shown as mounted at the edge of, for example, a shelf 16, and with one of the bullet catches located vertically over the other. The keeper member is secured at the inner face of a door 17. When the door is swung to closed position the pointed edge at 13, as previously described, forces the two catches apart until the heads seat in the slots 14. Opening of the door is accomplished by merely pulling upon the same whereupon the two catches are forced apart and the keeper is released.

While the keeper and its cooperating latch structure are shown mounted as has been described, it is evident that they can be turned 35 to different angles than those shown in Figs. 1 and 2, and that there are a great many places where the latch structure may be mounted other

than on the edge of a shelf, for example, at the inner side of a cabinet and with the keeper secured to the door so as to enter between the catches. The latch and its keeper may be reversed in position, that is, the latch secured to 5 the door and the keeper to the cabinet or a shelf thereof. The elongation of the slots 14 permits mounting of the parts without the necessity of extreme care in mounting, and also takes care of any variations such as shrinking, swelling or 10 warping of the materials from which the cabinet or the door is made.

After the latch has been fastened in position, the latch being shown in Fig. 6, the keeper may be forced therebetween whereupon the pressure of 15 the plunger heads 8 will hold it in position. While held in this position the door may be closed and the projections 15a brought to its proper position whereupon continued pressure will cause the projections to indent and thus after 20 the door has been again opened and the keeper removed, permanently fastened in position.

The invention is defined in the appended claims and is to be considered comprehensive of all forms of structure coming within their scope. 25

I claim:

1. In combination, a latch having a flat wing with screw holes therethrough, two spaced apart extensions extending at right angles to the wing, two catches including heads yieldably mounted 30 upon the outer ends of the extensions oppositely to the wing and juxtaposed to one another for the purpose described.

2. A combination of elements as set forth in 35 claim 1 in which the flat wing is cut away between the said extensions.

CHARLES L. FROST.
